N. S. Bedder and W. L. Sanderson - Troy N.Y.
Assors to
G. W. Eddy of Waterford N.Y.
Letters Patent No. 8461 - Dated Oct 21. 1856.

The Schedule referred to in these Letters Patent, and
making part of the same.

To all whom it may concern:

Be it known that
we N. S. Bedder and Wm L. Sanderson of Troy in
the County of Rensselaer and State of New York, have

invented or produced a new and original design for a Cook stove which we call the "Amazon" and we do hereby declare that the following is a full, clear and exact description of the same, reference being had to the annexed drawing making part of this Specification.

Our design for Cook stove is as follows, viz
 A, is the top plate with the wave moulding (a) forming the border, B is the upper front plate with the front doors C.C. which have ornamental corners (b.b.) and ornaments (c.c.) upon their panels. D is the hearth plate with the dotted moulding (d) terminating at the end in the scroll ornament (e). E is the lower front plate, having the ornaments (f) and (g.g) upon the panel. F is the jamb plate, with fire door G, having ornamental corners (h) and panel ornament (i). H and I, are oven doors, having respectively ornamental corners (j.j.) and panel ornaments (k.k.). J is the bottom plate with the ornamental moulding (l). K is the leg with the ornamental leaf (m) upon its face.

Having fully described our design for a Cook stove. What we claim as new, and desire to secure by Letters Patent is the ornamental design and configuration of Cook stove plates, such as herein described and shown in the annexed drawing.
